UNITED STATES PATENT OFFICE.

STANLEY BOUTIN, OF SPRINGFIELD, MASSACHUSETTS, ASSIGNOR TO WILLIAM E. GILBERT, GEORGE H. EMPSALL, AND HAROLD DUCKWORTH, TRUSTEES, ALL OF SPRINGFIELD, MASSACHUSETTS, DOING BUSINESS AS DUCKWORTH CHAIN & MANUFACTURING COMPANY.

MACHINE FOR DETECTING AND SORTING ARTICLES.

Application filed December 14, 1922. Serial No. 606,995.

This invention relates to an apparatus for detecting and sorting articles, such as flat plates, which have a right side and a wrong side and contemplates the provision of means for determining whether such a plate is right side up and if not right side up to turn it over, together with means for assembling or stacking the plates thus sorted all with their corresponding sides facing in the same direction.

The particular embodiment of the invention herewith illustrated is more especially designed to handle such articles as the side plates of roller chains commonly used in the driving mechanism of bicycles, motorcycles, etc., but it will be obvious that the general principles and advantages of the invention will be found applicable to a variety of uses.

The side plates of such roller chains are usually formed with, what is here termed for convenience of description, a right side having bevelled corners and a wrong side having sharp and unbevelled corners. The manufacture of such chains is greatly facilitated by having the side plates supplied with the same side thereof uppermost whereby they may be more readily assembled with the other elements making up the chain in the fabrication process. The apparatus of the present embodiment of the invention is therefore designed for the purpose of so arranging or sorting the side plates of such chains in order that they may be more easily handled in the subsequent operations of manufacturing the chain.

In the preferred embodiment of the invention shown in the drawings;

Fig. 1 is a side elevation of the machine showing certain details in section;

Fig. 2 is a detail section through a portion of the hopper bottom along line 2-2 of Fig. 7;

Fig. 3 is a similar detail section showing the entrance of the exit slot in expanded position;

Fig. 4 is an end elevation of the machine;

Fig. 5 is a perspective view of the receiving end of a discharge chute;

Fig. 6 is an enlarged view in cross-section of a discharge chute along line 6-6 of Fig. 1;

Fig. 7 is a view looking from above, of

the feeding hopper with end portions thereof cut away;

Fig. 8 is a view in cross-section of said feeding hopper along the lines 8-8 of Fig. 7;

Fig. 9 is a detail view partly in section of the stacking chamber;

Fig. 10 is a detail perspective of the lower end of a retaining latch located at the bottom of said stacking chamber;

Fig. 11 is a plan view of the base plate of the machine with parts mounted thereon and showing the stacking chamber in cross-section;

Fig. 12 is a view in section of the base plate of the machine along the line 12-12 of Fig. 10 and showing in side elevation the detector plunger and abutment.

Fig. 13 is a detail view showing the co-action of the plunger and abutment on an interposed plate;

Fig. 14 is an enlarged view of the abutment showing the curved abutting surface and shoulder thereof; and

Fig. 15 is a perspective view of a roller chain side plate such as is adapted to be handled in the present machine.

Referring more particularly to the drawings, the main frame of the machine consists of a bed or table top 1 supported on suitable legs 2. A pair of rigidly mounted supporting arms 3 extend from the main frame and carry at the end of their upturned portions tie rod 4 the latter serving as a bearing for a rocking feed hopper 5.

A base plate 1' mounted on the bed 1 serves as support for the detector and sorting mechanisms hereinafter more particularly described, together with magazines 6 for receiving plates (such as P, Fig. 15) fed from the hopper 5 preparatory to being detected and sorted and stacking chambers 7 for receiving the plates after they have been sorted and properly arranged. Inclined discharge chutes 8 rigidly mounted on the frame and bracket arms 3, lead from the feeding hopper to the magazines 6.

It will be observed that in the apparatus illustrated, three complete sets of discharge chutes, magazines, detector and sorting mechanisms, and stacking chambers are provided on one main frame but this triplicate arrangement of the parts named, is a mere

matter of convenience for increased output and it should be understood that each one of said sets operates independently of the other and in a similar manner.

Feeding hopper mechanism.

- The feeding hopper 5 is designed to contain a supply of plates P to be sorted and to feed said plates therefrom separately.
- 10 The plates are fed from the feeding hopper in a single column down one or the other of the discharge chutes 8 and the construction and operation of the feeding hopper for so feeding the plates will now be described. The hopper 5 may be of any suitable box like construction with a substantially flat bottom and open top and each end of the hopper may be partially covered at the top by overhanging portions 9 and 10 as shown. The hopper is mounted by a pivotal bearing on the tie rod 4 so that it may be rocked back and forth for agitating and sliding the plates contained in the hopper from end to end thereof. The means for rocking the hopper consist in the embodiment shown, of a rocking lever 11 pivoted at 11' on the main frame and having a cam roll 12 riding on a cam 13 which is fixed to a suitable cam shaft 14. The outer end of said rocking lever 11 is connected by rod 15 to said hopper. Suitable means such as a turn buckle 16 may be provided on the rod 15 for adjusting its length and varying the rocking movement.
- 25 The bottom of the hopper is formed preferably in two portions, a rear portion 17 and a forward portion 18 (see Fig. 2) and said bottom portions are preferably at a slight angle to one another and converge toward one or more exit slots, such as 19, formed through the bottom of the hopper. This exit slot 19 is preferably formed in alignment with the rear bottom portion 17 and is of such size as to permit only one plate at a time to pass therethrough. It will be observed from Fig. 2 that the receiving end of a discharge chute 8 is located adjacent the outer end of each exit slot 19.
- 30 In order to prevent a plate improperly aligned with said exit slot 19 from jamming therein and clogging the same, means are preferably provided for periodically expanding the entrance to said slot whereby any link caught therein will be released during the rocking of the hopper. This expansion of the entrance to said exit slot 19 preferably takes place on the backward rocking movement of the hopper 5, that is, when the rear end of said hopper is down. The expansion of said exit slot is accomplished as follows: Yieldingly mounted at the entrance to said slot 19 is a guard plate 20, the upper side of which forms continuation with the front bottom portion 18, and the lower side

of which forms the top wall at the entrance to said slot. The plate 20 is fixed to studs 21 which extend through the bottom portion 17 of said hopper and is normally held down to the position shown in Fig. 2 by springs 70 75 surrounding said studs 21. The guard plate 20 when in its lower position is spaced from the bottom of the slot 19 barely sufficient to allow a single plate to slide thereunder and the sharp forward edge of said guard plate 20 diverts other plates than the one passing thereunder to the forward bottom portion of said hopper. A raising movement is periodically imparted to the guard plate 20 to the position shown in Fig. 80 85 3 by means of a rocking lever 24 pivoted at 25' on the hopper bottom and connected at its rear end by rod 26 to the rocking lever 11. A turn buckle 27 may also be provided for adjusting the length of the rod 26. The 90 forward end of said lever 24 engages a pin plunger 25 slidably mounted and guided through the bottom 17 and having its upper end in engagement with said guard plate 20.

The rear bottom portion 17 of the hopper is 95 preferably formed with one or more straight channel grooves 28, there being as many of such channel grooves in this portion of the hopper as there are exit slots 19 and discharge chutes 8. Each of said channel 100 grooves is formed as a continuation of its respective exit slot 19 so as to direct plates which lie in said channel groove toward said exit slot during the forward rocking movement of the hopper. The channel groove 28 is of such dimensions as to permit only a 105 single row or column of plates to lie flatwise therein, this being accomplished by having the depth of the channel groove barely exceed the thickness of a plate P and its width barely exceed the width of a plate. Directing cleats 22 of various shapes may also be provided upon the bottom portion 17 of the hopper so as to divert the plates sliding back and forth in said hopper into 110 said channel grooves 28.

A stop pin 29 is arranged so as to protrude periodically into each channel groove and said stop pins are preferably mounted adjacent the entrance to the exit slots 19 so as 115 to assist in clearing any jam of plates that might occur at said entrance. The rocking of the hopper 5 periodically aligns each channel groove 28 and exit slot 19 with its respective discharge chute 8 as shown in Fig. 2 and the stop pins 29 are moved into the channel grooves 28 so as to block the plates in said channel grooves from sliding out said exit slots 19 until just at the time said exit slots are aligned with the discharge 120 chutes 8. The pins 29 are then withdrawn to permit the plates P to slide into the discharge chutes 8. The stopping pins 29 are 125 preferably guided through the bottom 17 of the hopper and are loosely connected at their 130

lower ends to a rocking plate 30 which is pivoted at 37 to a bracket secured to the bottom of the hopper. A spring 29 surrounding each pin 29 serves to cushion the upward movement imparted to the pin by the plate 30 and further to allow the pin to yield when striking a jam of plates. The rocking plate 30 is moved by link 31 connected to cam lever 32 pivoted at 33 on a bracket of the main frame and having a bearing member 35 riding upon a cam 36 which is fixed to said cam shaft 14.

Detector and sorting mechanism.

15 The plates fed from the hopper 5 through the several exit slots 19 are guided by the discharge chutes 8 to the magazines 6 preparatory to being delivered to the detector and sorting mechanism. The discharge chute 8, as shown in Figs. 5 and 6, provides a channelled passageway for guiding the column of plates flowing therethrough, the bottom of said passageway at suitable portions thereof, being slotted, as at 39, to permit egress of the accumulated dirt, or of under size plates. The upper end of each discharge chute 8 is provided with a yieldingly mounted cover plate 40 in the form of a spring member fastened at one end to the chute, as at 41, and having at its free end a bearing member 42 extending partially into the channel groove of said chute 8 so as to determine the size of the receiving end of said channel chute. The purpose of mounting said cover plate 40 in a yielding manner, as shown, is to allow the same to give way whenever a plate happens to lie partly in the exit slot 19 and partly in the receiving end of the chute 8 when the feeding hopper 5 is rocked backwardly.

Since each of the three mechanisms here-with shown for detecting and sorting the plates are alike, it will suffice to describe one of them in detail. The magazine 6 is preferably made in the form of a block having an upwardly opening recess 38 which is of such shape and dimensions as to receive a plurality of plates P piled one above the other. The bottom of the recess 38 is provided by the base plate 1', upon which the magazine 6 is mounted and the lower end of the discharge chute 8 is covered by a guard member 39 (see Fig. 11) which normally extends across the top of the chute 8 and limits the number of plates which may be piled in said magazine.

The detector and sorting mechanism specifically comprises an abutment block 43 mounted on the base plate 1', and a sliding detector plunger 44, said parts being moved in proper coactive relation as hereinafter described for detecting and sorting the plates. As shown in Figs. 12, 13, and 14, the abutment 43 has a concave abutting surface 45 with a slight shoulder 46 at the lower end

thereof adjacent the base plate 1'. The forward end of the plunger 44 is slotted, as shown in Fig. 11, and is formed with vertical faces 47 for engaging the edges of a plate P interposed between said plunger 70 and the abutment 43. The abutment 43 is likewise slotted, and mounted on the abutment and extending within said slots is a pivoted holding member 58 normally pressed downwardly by a spring 59 and adapted to extend across the path of the plate interposed between plunger and abutment.

The plates P are fed successively one by one from the bottom of the magazine 6 to a position between said plunger and abutment, as shown in Fig. 11, by means of a reciprocating slide finger 48 which works through the bottom of said magazine 6 along the top of said base plate 1'. The slide finger 48 is carried by slide bar 49 suitably guided on said base plate 1' and connected at its outer end by link 50 to rocking lever 51 pivoted at 51' on the main frame and having cam roll 52 working against a cam 53 mounted on cam shaft 54. A spring 55 connected to said lever 51 and to a portion of the main frame, tends to keep said cam roll 52 in bearing engagement on its cam 53. Each plate fed from the magazine 6 to a position 95 between said plunger 44 and abutment 43 is yieldingly held in flatwise position therebetween and on the base plate 1' by means of the holding member 58. As each plate P reaches this position, the plunger 44 is yieldingly moved against the same to force the edge of the plate against said abutment 43. The plunger 44 is guided for slidable movement along the top of the base plate 1' within a housing 56. The outer end of said plunger 44 carries a spring stud 57 connected by spring 60 to a stationary spring stud 61 mounted on said housing 56, whereby said plunger has a constant tendency to move to the right, looking at Fig. 12. The plunger 100 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

It will be noted from Fig. 15 that the particular form of plate to be detected or sorted in the present machine is a flat member with slightly bevelled corners, at one side thereof, and sharp unbevelled corners at the other

side thereof. The present machine is designed to arrange or sort said plates with the bevelled side uppermost. For this purpose, the shoulder 46 at the lower edge of the abutting surface 45 is carefully designed to be of just sufficient height to arrest a plate P which presents a sharp or unbevelled corner thereto when pressed thereagainst by the detecting pressure of the plunger 44. The shoulder 46, however, is designed not to arrest a plate P which presents a bevelled corner thereto whereby pressure from said detecting plunger will cause the bevelled edge of such a plate P to ride upwardly 15 against the concave abutting surface 45, as shown in Fig. 12. The curved abutting surface 45 is extended far enough to guide the upturned edge of said plate P completely around to an overturned position 20 of the plate. As the plate thus reaches its turned over position, the plunger 44 is timed to withdraw to the left for allowing said plate to be fed forward by the next incoming plate. The holding member 58 which 25 gives way during the turning over movement of the plate, will immediately press said plate downwardly flat against the base plate 1' in its right side up position.

The foregoing action takes place quickly 30 and between intervals of feeding plates from the magazine 6, so that by the time a succeeding plate is fed from said magazine 6, the previous plate has either been detected and allowed to remain unturned, or has been 35 overturned to its right side up position, whereby the succeeding plate in being fed forward between the plunger and abutment will thrust the previous plate ahead of it to a position beneath a guide strap 66 (see 40 Fig. 11). From this position the plate is fed by the following plate upon the next succeeding step into a position beneath the stacking chamber 7.

Stacking mechanism.

As each plate is thus fed forward to a position beneath the open end of stacking chamber 7, a vertical plunger 67 (see Figs. 1 and 9) is periodically moved upwardly to 50 carry said plate upwardly into said stacking chamber. The lower end of said chamber 7 is provided with holding latches 68, the lower edge of which is bevelled at 69 as shown in Fig. 10, which act to retain the 55 plates in said stacking chamber as fast as they are moved upwardly therein. The plunger 67 is guided through the base plate 1' for vertically reciprocating movement and is actuated by a connecting rod 68' 60 pivotally carried at its lower end upon rocking lever 69. The rocking lever 69 is pivoted at 70 upon the main frame and carries a cam roll 71 working against a cam 72 fixed to said cam shaft 54. A spring 73 65 connected to the main frame and to the outer

end of said lever 69 tends to hold said cam roll in working engagement with the cam.

Operation.

The operation of the machine, while 70 clearly apparent from the previous description, is briefly as follows:

The plates P contained in the hopper 5 are slid back and forth along the bottom of said hopper by the rocking movement thereof of which action causes a supply of plates to find their way into the channel grooves 28 out of the exit slots 19, and down the discharge chutes 8 to the magazines 6.

From the bottom of each magazine the 80 plates are fed forward successively by a slide finger 48 to a position between a detector plunger 44 and abutment 43. The transversely movable detector plunger 44 is then allowed by its actuating cam 65 to press the 85 plate P against the abutment 43. In this manner the detecting action occurs, for if the plate P be right side up, its unbevelled corner will be arrested by the shoulder 46 of the abutment 43, and no overturning 90 movement thereof will take place. Should, however, the plate P be wrong side up, its bevelled corner will ride over the shoulder 46, and the plate guided by the curved surface 45 of the abutment 43 will be overturned. The parts are so timed that this detecting and overturning action of the plate takes place between the intervals of feeding plates from the magazine 6, and the slide finger 48 thus feeds plates one in advance 100 of the other successively through the detecting and sorting mechanism to the stacking chamber 7. Here the plates are carried up the vertical chamber 7 by the reciprocating plunger 67 and are ready for removal.

I am aware that various detail changes in the apparatus as shown may be made and the general arrangement altered in many respects while still employing the essential and novel features of the invention in the 110 attainment of the same results. Accordingly, I do not wish my invention to be limited to the precise embodiment shown but rather to be determined by the appended 115 claims interpreted broadly.

What I claim is:

1. In a machine of the class described in combination, a hopper for containing a supply of plates to be sorted, each plate having a right side with a bevelled corner and a wrong side with an unbevelled corner, means for feeding said plates separately from said hopper, detector and sorting mechanism for determining which side of each plate thus fed is uppermost and acting to turn over 125 any such plate the wrong side of which is uppermost and a chute to receive the said plates.

2. In a machine of the class described, a 130 table for supporting a magazine for holding

- a stack of unsorted plates and a magazine for holding a stack of sorted plates, members between said magazines to form a guideway for the passage of plates therebetween, 5 means for feeding plates through said guideway, means associated with said guideway for reversing certain of said plates during their passage therethrough, an elevator below one of said magazines for elevating 10 plates as they are delivered thereonto, and members carried by the walls of said magazine for holding the lowermost plate of the stack above said support to allow successive plates to be fed therebelow.
- 15 3. In a machine of the class described, a magazine for holding a stack of unsorted plates and a magazine for holding a stack of sorted plates, each plate having a right side with a bevelled edge and a wrong side 20 with an unbevelled edge, a guideway connecting said magazines, a member for feeding plates therethrough successively, a portion of one side wall of said guideway being curved upwardly and inwardly, and a 25 plunger movable towards and away from said portions adapted to engage a side edge of successively fed plates arranged to cooperate with said side wall for reversing such plates as have their wrong sides uppermost.
- 30 4. In a machine of the class described, separate magazines for holding stacks of plates which have right and wrong sides with bevelled and unbevelled edges respectively, a guideway connecting said magazines, means for feeding plates successively through said guideway between said magazines, a portion of one side of said guideway being curved upwardly so as to overlie plates 35 therein and a plunger movable towards and away from said portion for engaging a side of said plates and adapted to cooperate with said side to reverse such plates as have their wrong sides uppermost.
- 40 5. In a machine of the class described, a table for supporting a magazine for holding a stack of unsorted plates and a magazine for holding a stack of sorted plates, a guideway between said magazines, means associated with said guideway for reversing certain of said plates, an elevator below one of said magazines for moving plates delivered thereonto upwardly into said magazine and yieldable stop members above said support 45 and associated with a wall of said magazine for engaging the plates as they are moved upwardly by the elevator whereby the stack is supported by the lowermost plate.
- 50 6. In a machine of the class described in combination, detector and sorting mechanism
- for plates having a right side and a wrong side, said detector and sorting mechanism comprising a plunger and a curved abutment having a shoulder at its lower edge, co-acting to detect which side of a plate fed thereto is uppermost and to turn over any plate the wrong side of which is uppermost, and means for feeding plates to said detector and sorting mechanism.
- 65 7. In a machine of the class described in combination, detector and sorting mechanism for plates having a right side with a bevelled corner and a wrong side with an unbevelled corner, said detector and sorting mechanism comprising a plunger and a curved abutment, means for feeding plates between said plunger abutment, means for periodically moving said plunger toward said abutment in a yielding manner, said abutment having a shoulder at its lower edge 70 designed to arrest a plate which presents an unbevelled corner thereto and to allow a plate presenting a bevelled corner thereto to be turned over by the coaction of said plunger and curved abutment.
- 75 8. In a machine of the class described in combination, detector and sorting mechanism for plates having a right side with a bevelled corner and a wrong side with an unbevelled corner, said detector and sorting mechanism comprising a plunger and a curved abutment, means for feeding plates in flatwise position between said plunger and abutment, a yielding member tending to hold each plate flatwise between said plunger and abutment, means for periodically moving said plunger toward said abutment in a yielding manner, said abutment having a shoulder at its lower edge 80 designed to arrest a plate which presents an unbevelled corner thereto and to allow a plate presenting a bevelled corner thereto to be turned over by the coaction of said plunger and curved abutment.
- 85 9. In a machine of the class described in combination, detector mechanism for plates having a right side with a bevelled corner and a wrong side with an unbevelled corner, said detector mechanism comprising a plunger and an abutment, means for feeding plates between said plunger and abutment, means for periodically moving said plunger toward said abutment in a yielding manner, said abutment having a shoulder designed to 90 arrest a plate which presents an unbevelled corner thereto and not arrest a plate which presents a bevelled corner thereto.
- 95 100 10. In testimony whereof I have affixed my signature.
- 110 115 STANLEY BOUTIN.
